DESIGN FOR A COMBINED BRACELET AND WATCH

William M. Welling, New York, N. Y.

Application January 12, 1940, Serial No. 89,432

Term of patent 3½ years

To all whom it may concern:

Be it known that I, William M. Welling, a citizen of the United States, residing at New York, in the county of New York and State of New York, have invented a new, original, and ornamental Design for a Combined Bracelet and Watch, of which the following is a specification, reference being had to the accompanying drawing, forming part thereof.

Figure 1 is a perspective view of a combined bracelet and watch, showing my new design; and Figure 2 is a top plan view of the same.

I claim:

The ornamental design for a combined bracelet and watch, as shown.

WILLIAM M. WELLING.
